UNITED STATES PATENT OFFICE.

FERDINAND J. ROCHOW, OF BROOKLYN, NEW YORK.

COMPRESSOR, VACUUM-PUMP, AND THE LIKE.

No. 921,164.

Specification of Letters Patent.

Patented May 11, 1909.

Application filed May 31, 1906. Serial No. 319,454.

To all whom it may concern:

Be it known that I, FERDINAND J. ROCHOW, of Brooklyn, in the county of Kings, New York, have invented certain Improvements 5 in Compressors, Vacuum-Pumps, and the Like, of which the following description, in connection with the accompanying drawings, is a specification, like characters on the drawings designating like parts.

10 This invention relates to compressors of air or other gases, including so-called vacuum-pumps, and especially to such forms of the same as are operated by a reciprocating piston.

15 The object of my invention is first to neutralize, practically completely, in the aforesaid type of compressors and vacuum-pumps, the loss of efficiency caused by the compressed gases remaining on the suction side in 20 clearance spaces between the piston and cylinder head and in those of inlet and outlet channels of suction and delivery valves, when the piston has reached either end of its stroke. In existing apparatus of this type, 25 these compressed gases, when thus confined, expand as the piston commences its return movement and prevent the opening of the suction valves until the pressure of the expanding gases is as low, or a trifle lower, than 30 that in suction side; until then the piston can do no work; it is only from the moment that suction commences that action of the piston commences. That part of the stroke of the piston thus traversed is a total loss to 35 the theoretical efficiency of the piston, as the latter is a function of the total stroke of same.

40 A second object of my invention is to increase the efficiency on the compression side, by transferring from the suction to the compression side, the bulk of these confined gases.

45 The nature of my invention resides first in providing a separate passage between the two sides of a compressor cylinder, separated by the piston, and second in providing means so acting that when the piston is at either end of its stroke the gases compressed within 50 clearance spaces will be practically transferred from these clearance spaces to the opposite side of the piston. It is evident from the above description that the aforesaid passage may be located either within the piston or outside of same, within or connected with the cylinder.

For reasons to which I will refer later, I 55 will describe herein an embodiment of the second system, providing a separate passage in cylinder.

My invention is of such general utility that it is not to be understood as confined to one 60 special construction or device described, as it is easily applicable to any apparatus of a reciprocating piston type.

65 The following specification and its accompanying drawings, forming a part of same, 65 describe my invention as applied to a simple type of compressor and will make the character of my invention, its operation and one convenient form of construction, perfectly clear to the mechanic skilled in the art, and 70 will not only enable him to reproduce the device on similar types of compressors, but will make easily apparent to him how to apply the invention to any other type, as the invention is so simple that it is only a matter of 75 ordinary engineering routine to apply it to any style or construction of a reciprocating piston compressor.

In the drawings, Figure 1 is a vertical section through the center line A—B of a cylinder belonging to a compressor or vacuum pump; Fig. 2 is a top view of the cylinder head of same taken from line C—D; Fig. 3 is a cross section through the cylinder by the line E—F; Figs. 4 and 5 a front view and sectional side elevation of the general arrangement of a complete compressor or vacuum pump; Figs. 6 and 7 are detail views of the housing of suction valves; Fig. 8 is a detail view of cam for operating suction valves; 80 and Fig. 9 a detail view of cam for operating equalizing valves.

85 In the embodiment of my invention selected for illustration and description as a convenient form to enable ready and complete understanding of my invention, the part designated by the reference numeral 1 is the cylinder of a gas or air compressor; 2 its piston; 3 its piston-rod; 4 the cylinder head; 5 the cylinder bottom; 6 a channel for 100 the discharge of the compressed gases, and 7 (see Figs. 2, 3, 4 and 5) a channel for the suction of the gases. 8 designates suction valves and 9 the discharge valves. These 105 constitute the necessary parts of an ordinary compressor, while my improvement consists principally in a channel 10, establishing a direct communication between the two ends

of the cylinder 1, preferably without any other inlet or outlet, and valves 11 which are located one at each end of this channel, preferably opposite the suction valves so as 5 not materially to increase the clearance space of the channel 12 (see Fig. 1). The valves 11 are positively opened and shut by means of levers 13, spiral springs 14 and cams 15 (see Figs. 3, 4 and 5), in such a way 10 that each one opens and shuts during a very short period of the rotation of the crank-shaft 24 and at a moment when the piston passes either end of its stroke. The levers 13 are supplied at their outer ends with steel rollers 16 rolling along the periphery of cams 15. The suction valves 8 are similarly and 15 positively operated by means of levers 18, springs 19 and cams 17, which latter are shaped and adjusted in such a way that the valve 8 on the piston side commences to 20 open a trifle after the valves 11 have shut and that valve 8 away from piston shuts a trifle before valves 11 have opened. The discharge valves 9 are ordinarily used automatically working check-valves, with stems 25 guided in covers 21, and spiral springs 22 to seat them automatically. Figs. 4 and 5 show the general arrangement for the operation of the positively driven valves.

30 The parts designated by the reference numeral 23 are two A frames supporting the compressor cylinder below and the crank shaft above, with guides in middle for cross-heads 25. The bottom cylinder head 5 is bolted by means of two cross beams 26 to frames 23 while the tops of these frames form pillow blocks 27 in which crank shaft 24 revolves. On that end of the crank shaft 35 nearest to the suction and equalizing valves is fastened firmly a spiral gear 28 which meshes into another spiral gear of the same number of teeth 29 and which is fastened permanently to the top of an auxiliary shaft 30, so that both these shafts make exactly 40 the same number of revolutions, and the frame 23 is furnished with three bearings 31, guiding the shaft 30, and lastly the four disk-cams 15 and 17 are fastened to said shaft and adjusted properly opposite 45 levers 13 and 18 so that the opening and closing of valves 8 and 11 is done in the required relation to the position of the crank in every revolution of the crank shaft.

50 From the above description we can easily trace the operation of the device as follows:—As the piston travels one way or the other there is always suction of gases behind it, the suction valves being open almost during the whole stroke, and compression in front of it, the discharge valves opening automatically to 55 allow escape of the gas under compression. When the piston has almost reached the end of its stroke, the suction valves are positively closed and immediately after this i. e. immediately prior to or after commencement of

the suction stroke, when all possible compression shall have been accomplished, the equalizing valves are opened and the compressed gas in front of the piston will rush immediately through channel 10 into the other side 70 of the cylinder (whereby the discharge valve of the piston side will also instantly close) until the pressure of gases will be equalized within the cylinder, on both sides of the piston. This equalization will be obtained 75 very quickly and the equalizing valves must only be opened a very short time as they ought to be shut when equalization has occurred. As the space in front of piston is only very small at the moment when equalizing valves open, the equalized pressure in front and behind piston will be only slightly above the pressure on the suction side when the equalizing valves close, and a slight motion of the piston after reversal will suffice 80 to create a sufficient vacuum on that side of the piston which is now retiring from the cylinder head, to allow suction through suction valve, which latter is opening at this stage of the travel of the piston. Thus it is 85 seen that the suction will last almost during the whole stroke of the piston and that the loss of efficiency by reason of clearance spaces at end of stroke of piston as far as suction is regarded is insignificant. After equalization about 80% of the quantity of the compressed air which was confined before it in clearance spaces has been transferred to the opposite or compression side of the piston and thereby the capacity of the compressor 90 increased to a certain extent. In order to exemplify the insignificance of said respective loss and the amount of said respective gain in capacity, and to facilitate comparison between this improved compressor and the ordinary style, we will assume that the capacity of the cylinder, meaning the product of area and stroke of piston, may be named l , the sum of clearance spaces on either end of cylinder X, the pressure on the compression side of piston p and the pressure on suction side of same v . When piston arrives at either end of its stroke, the gases within cylinder will be distributed as follows:—In front of piston will be a space x filled with gas at a pressure P , and behind the piston will be a space 1 plus x filled with gas, at a pressure v . The equalizing valves 100 110 open and shut now in quick succession, allowing only time enough when open to obtain equalization of pressure on both sides of cylinder; thus the air confined in x with pressure P expands now into a total space of 1 plus $2x$, therefore its pressure will be reduced to 115 120 125

$\frac{xp}{1+2x}$

and the air confined in space 1 plus x , with a pressure of v , expands likewise into the total 130

space 1 plus $2x$ and will attain after expansion a pressure of

$$\frac{(1 + x)v}{1 + 2x}.$$

5

The sum of both the pressures is the total equalization pressure, equals

$$10 \frac{x \text{ times } p \text{ plus } \frac{(1 + x)v}{1 + 2x}}{1 + 2x} \text{ equals } \frac{xp + (1 + x)v}{1 + 2x}.$$

A few numerical examples will now clearly 15 establish the great advantage of my invention, compared with the usual type.

First example:

Let v equal 1 (atmosphere)

$$20 \frac{p}{x} \frac{5}{0.02} \quad (\quad)$$

If we substitute these figures in above formula, we have pressure after equalization equals

$$25 \frac{5 \text{ times } 0.02 \text{ plus } 1.02 \text{ times } 1}{1.04} \text{ equals } 1.07 \text{ atmospheres.}$$

The amount of clearance spaces is 0.02; 30 when this is increased to 0.02×1.07 the pressure will be reduced to 1 atmosphere and the action of the piston on suction side will commence then, 0.02×1.07 equals 0.0214; if therefore piston has traveled only 0.0214 – 35 0.02, equals 0.0014 of its stroke, suction will commence and the efficiency of the work of piston on the suction side will be $1 - 0.0014$, equals 0.9986; the pressure on compression side has increased by equalization from 1 to 40 1.07 atmosphere. Therefore the gain on this side is 0.07 and deduct from this the aforesaid loss of 0.0014 gives a total gain of 0.07 – 0.0014, equals 0.0686, or a gain of almost 7% beyond the theoretical efficiency of 1. Where 45 there is no equalization, however, the gases in clearance spaces 0.02 have to expand 5 times before atmospheric pressure is reached and suction commences, that is, 5×0.02 equals 0.1 and therefore $0.1 - 0.02$ is 50 the travel of piston required until then, so that 8% of the total efficiency is lost in this case. The comparison shows therefore in this case a total loss of 8% and on the former case a gain of 6.8% or a total difference in 55 favor of equalization of 14.8%.

Second example:

Let v equal 1 (atmosphere)

$$60 \frac{p}{x} \frac{5}{0.04} \quad (\quad)$$

The pressure after equalization by substitution will be

$$65 \frac{5 \text{ times } 0.04 \text{ plus } 1.04}{1.08} \quad (\quad)$$

or 1.148 atmosphere, and this multiplied by the amount of clearance spaces 0.04, and less clearance space, will leave amount of travel of piston before suction commences; i. e., $1.148 \times 0.04 = 0.04$ equals 0.148×0.04 70 equals 0.00592, or slightly over $\frac{1}{2}$ of one per cent. of the travel of stroke is here lost on theoretical efficiency on the suction side of piston, while the actual gain on compression side after equalization is $1.148 - 1$ equals 75 0.148, therefore here total gain again equals $0.148 - 0.00592$ equals 0.14208, while the loss without equalization is $(5 - 1)0.4$ equals 0.16. Thus the comparison in this example is as 16 plus 14.2 equals 30.2 per 80 cent. in favor of the equalization system. This example shows that the amount of clearance space affects the efficiency of this invention only very slightly, while when equalization is not used the suction will 85 commence when the piston has traveled $(5 - 1)0.04$ equals 0.16, or 16% of its stroke. The losses in this case compare therefore as 0.00592 to 0.16, or as 1 to 27 in favor of my improvement. 90

Third example:

Let v equal 1 (atmosphere)

$$p \frac{26}{x} \frac{(\quad)}{0.04}$$

95

Here the pressure after equalization is

$$26 \frac{26 \text{ times } 0.04 \text{ plus } 1.04}{1.08} \text{ equals } 1.92 \text{ atmosphere,}$$

100 and the travel of piston before suction commences equals $(1.92 - 1)0.04$ equals 0.0368 or only 3 and $\frac{1}{2}$ per cent. of the theoretical efficiency is here lost on suction side while the gain in quantity on compression side is 105 $1 - 1.92$ atmosphere equals 0.92 atmosphere, and the subtraction of loss from gain equals $0.92 - 0.0368$ leaving a total gain by equalization of 0.8832, while in an ordinary compressor, without equalization, the pressure on suction side of piston will reach the pressure of the atmosphere when it arrives at 110 the end of its stroke, namely

$$115 \frac{26 \text{ times } 0.04}{1.04} \text{ equals } 1,$$

and the compressor will not be able to do any work, against work equivalent to 1.8832 efficiency, when my equalization system is 120 adopted.

The specification and drawings explain so far only the application of my invention on so-called double acting compressors or vacuum pumps, but it is evident that the same 125 arrangement may be applied also to single acting cylinders with a suction valve on one side and a discharge valve on the other. It is also evident from the description given so far that the same system could be applied by 130

making a direct passage within the piston from one side of it to the other, instead of within the cylinder and by devising mechanism for positively operating equalizing valves 5 to control communication through such passage, but it is so important in all mechanism operating valves to provide for the greatest possible facility for taking out valves for inspection or repairing and also for the quick 10 and reliable readjustment of their motion, that I prefer to describe a device comprising a passage outside of cylinder, and valves and valve-motion which are under constant supervision and if necessary can be taken apart 15 quickly.

The general practice now adopted in compressing to a high pressure is compounding a number of compressors, one compressing into the other one, in order to diminish their 20 enormous loss of efficiency as much as possible, but with the adoption of my simple device of the passage and two valves, a single cylinder is sufficient to compress to the highest pressure in practical use, not only without loss of efficiency but with a considerable 25 gain of same on account of filling the whole cylinder of a compressor by equalization at end of stroke of piston, with a higher pressure than the atmospheric pressure and 30 therefore increasing its natural capacity. For instance if the compression is assumed to be 100 atmospheres and the clearance space in each end of cylinder to be 0.015 then the equalization pressure will be 35

$$\frac{100 \times 0.015 + 1.015}{1.03} \text{ or } 2.4.$$

The travel of the piston from the end of its 40 stroke until suction commences will therefore be $(2.4 - 1) \times 0.015$ or 0.02 or 2 per cent. of its whole travel, so that there is only a loss of 2 per cent of the theoretical efficiency on the suction side, compressing in a single cylinder from 15 pounds (i. e. atmospheric pressure) on the one side to 1500 pounds of pressure on the other side. The gain on compression side is $2.4 - 1$ equals 1.4 atmosphere, hence total gain equals $1.4 - 0.02$ 45 equals 1.38, so that the capacity of a compressor of my improved system under these conditions would be actually 138 per cent. larger than a theoretically correct compressor without this system could attain, 50 showing an efficiency of 2.38. A single cylinder compressor of the ordinary reciprocating style however could not attain any suction whatever and therefore could do no work whatever, under the conditions just described. 55

As a so called vacuum pump is nothing else but a compressor of gases, compressing them from a very rarefied state into the atmosphere, and as the accompanying drawings represent not only the arrangement 60

most preferable for a compressor, but also, without any change in any of its details, for a vacuum pump, it remains to show the advantage of this invention when the pump is intended for that purpose. We have here a 70 compressor which shall compress on one side to 15 lbs. (or atmospheric pressure) to the square inch, and on the other side it shall reduce the inhaled gases to the lowest possible pressure, but the lowest possible pressure on suction side is evidently reached when the piston is unable to discharge any more gas at atmospheric pressure, it being only able to fill clearance spaces with atmospheric pressure, because as there is then no 80 discharge, neither can there be suction any longer. If we now assume the clearance spaces to be 0.01, and again the capacity of piston travel to be 1, we can reason as follows: In order that the piston be able to just 85 fill 0.01 of the cylinder with a pressure of 15 lbs. and no more, the pressure at commencement of stroke, but after equalization, must have been 0.15 lbs. While this is compressed on one side of the traveling piston 90 and finally fills at end of stroke the clearance spaces with gases of 15 lbs. pressure, a rarefaction of gases occurs on its other side which finally, at the end of its stroke, must amount to $\frac{0.15}{100}$ or 0.0015 lbs., 0.15 lbs. being 95 the equalization pressure when suction starts, and this is the lowest pressure attainable with such clearance space. As these light pressures are generally measured by the 100 mercury gage and $\frac{2}{3}$ of the same is equal to a pressure of 1 lb. we have on the suction side a pressure as low as 0.003 inches, corresponding to a vacuum of 29.997 inches. If 105 we compare this result in a vacuum pump in a manner analogous to the comparisons we made before with compressors, we find that in a vacuum pump without equalization and under otherwise the same conditions, (viz., clearance space to be also 0.01 and compression to be just sufficient to fill this 110 clearance space with gases of 15 lbs. pressure), the greatest rarefaction attainable will be .15 lbs., or 0.3 inches mercury, or just 115 100 times more pressure remaining than in the case of the vacuum which we can obtain with the same pump by applying my system of equalization. The result in applying this system on vacuum pumps is therefore the same as that obtained in a compressor, 120 namely that by its application we can attain practically any amount of vacuum with only one cylinder, while the compounding of a number of cylinders for this purpose, or a vacuum pump, is even more necessary than 125 on a compressor, when used without my equalizing system.

Although I have described my invention as preferably using puppet valves and a certain style and operation of cams, I do not 130

confine my invention to these special devices as I may under certain conditions prefer to use slide valves, or reciprocating Corliss valves, or rotary valves, and as I may prefer under such conditions to arrange the cam motion differently to conform better to circumstances, I do not limit myself to the specific illustrated construction of any such details, nor in general otherwise than as set forth in my claims, read in connection with this specification.

What I claim and desire to secure by Letters Patent is:—

1. The combination with a cylinder and its reciprocating piston, of a passage, channel, or chamber in communication with the two sides of said cylinder, to transfer the residual compressed fluid from the clearance to the other end of said cylinder immediately prior to or after commencement of the suction stroke of said piston, and means actuated positively thereupon to prevent retransference of fluid through said passage, substantially as described.

2. The combination with a cylinder and a reciprocating piston therein, of a chamber, channel or passage, forming at times solely a communication between the two sides of said piston, to transfer residual compressed fluid from the clearance; valves for said passage to control said communication; and means to operate said valves; said instrumentalities coöperating to insure initiation of effective suction co-incident with the commencement of the suction stroke of said piston, substantially as described.

3. In combination with a cylinder, a reciprocating piston therein, a channel forming at times only a communication between both ends of said cylinder, valves for controlling said communication, to permit transference, immediately prior to or after commencement of the suction stroke, of compressed fluid to cause decreased pressure on the suction side, and increased pressure on the compression side, during said suction stroke, and positively driven suction valves which are timed to open and shut in proper conjunction with the operation of said controlling or equalizing valves, so as to insure initiation of suction immediately after completion of said equalization, and upon commencement of the suction stroke of said piston, substantially as described.

4. The combination with a cylinder, a reciprocating piston therein and its crank shaft, of a channel forming at times only a communication between both ends of said cylinder, and valves for controlling said communication, including a plurality of positively driven valves, an auxiliary shaft driven from the crank shaft by means of two gear wheels of an equal number of teeth, and

cams actuated by said auxiliary shaft for the operation of all said positively driven valves. 65

5. The combination with a cylinder, and a reciprocating piston therein, of a channel forming only a communication between both ends of said cylinder to transfer compressed fluid from one end of said cylinder to the other, for the purpose set forth, valves located at the ends of said channel for controlling said communication, and suction valves located opposite said controlling or equalizing valves said valves being respectively directly adjacent the clearance of said cylinder, and having a common communication thereto.

6. In combination with a cylinder, a reciprocating piston therein, a channel forming only a communication between both ends of said cylinder, to transfer compressed fluid from one end of said cylinder to the other for the purpose set forth, valves for controlling said communication; the auxiliary shaft 30; 85 cams 17 on same; suction valves 8; levers 18 and springs 19.

7. In communication with a cylinder, a reciprocating piston therein, the channel 10 to transfer compressed fluid from one end of 90 said cylinder to the other for the purpose set forth; valves 11; spiral springs 14; and levers 13 with an auxiliary shaft 30; gear wheels 28 and 29 and cams 15.

8. The combination with a cylinder and its reciprocating piston of a continuous passage, channel or chamber, forming a communication between the two ends of said cylinder, and means to transfer the residual, compressed fluid from the clearance spaces 100 of one end of said cylinder to the other end of same immediately prior to or after the initiation of a new suction of said piston, and means to prevent a retransference of any fluid during the remainder of the stroke, substantially as described. 105

9. The combination with a cylinder and a reciprocating piston therein, of a chamber, channel or passage, forming at times solely a communication between the two sides of said piston, to transfer residual compressed fluid from the clearance spaces, valves for said passage to control said communication, and means to operate said valves; said instrumentalities coöperating to insure initiation 110 of effective suction as well as most effective capacity in compressing, all co-incident with the commencement of the suction stroke of said piston, substantially as described. 115

Signed at New York city in the county of New York and State of New York this 26th day of May A. D. 1906.
